BOILER AND FURNACE INSTALLATION

Fay Harry Rosencrants, Scarsdale, N. Y., assignor
to Combustion Engineering Company, Inc., New
York, N. Y., a corporation of Delaware

Application May 31, 1934, Serial No. 728,314

8 Claims. (Cl. 122—235)

This invention relates to improvements in boiler and furnace installations having a horizontal type of boiler and a furnace or combustion chamber provided with boiler parts such as steam evaporating tubes defining the walls thereof—
5 installations of high capacity.

Among other objects of my invention, which will appear as the description of the invention proceeds, are the provision in an installation of the above character, of connections between the horizontal boiler and the furnace wall tubes whereby common circulation can be effectively employed; of connections enabling the boiler and the furnace wall tubes to be suspended with freedom for independent expansion and contraction without encountering difficulties in the connections; of means ensuring proper distribution in supplying the wall tubes from the boiler; and of means providing relief for certain boiler parts such as will ensure effective circulation.

How the foregoing together with such other objects and advantages as may hereinafter appear or are incident to my invention are realized, is illustrated in preferred form in the accompanying drawings, wherein—

Fig. 1 is a sectional elevation of a boiler and furnace installation constructed in accordance with my invention.

Figs. 2, 3, and 4 are fragmentary elevational views illustrating modified connections between the main boiler and the tubular walls of the furnace or combustion chamber.

Figs. 5 and 6 are fragmentary views illustrating relief connection which may be employed in the main boiler.

Fig. 7 is a sectional elevation of an installation illustrating a modified arrangement of steam evaporating tubes and circulatory connections.

Fig. 8 is a fragmentary view illustrating a modification in downcomer connections for the main boiler.

Fig. 9 is a fragmentary end view of Fig. 8.

Fig. 10 is a fragmentary view of other modified connections between the furnace wall tubes and the main boiler.

Fig. 11 is an elevational view of an installation illustrating a modification in the main boiler and in the circulatory connections between the water walls and the boiler.

Fig. 12 is a fragmentary detailed view of a modification in the nipple connections between the upper and lower headers of the main boiler.

Referring more particularly to Fig. 1 of the drawings, the boiler and furnace installation comprises in general a boiler A, a furnace or com-

bustion chamber B, burner means C of any suitable type for admitting fuel into the combustion chamber, suitable casing D for the installation, and structural work E from which the boiler and associated parts are suspended in a manner hereinafter appearing.

The boiler A is of the horizontally inclined tube type and comprises two spaced sections or banks of horizontally inclined tubes 15 and 16, the tubes 15 of the upper bank or section being connected at their lower ends into a plurality of downtake or downcomer headers 17, and at their upper ends into a plurality of uptake or upcomer headers 18, and the tubes 16 of the lower bank or drop section being similarly connected into a plurality of downcomer headers 19 and upcomer headers 20. The boiler headers are of the sectional type and may be sinuous, with the tubes arranged in staggered relation or straight, with the tubes arranged in aligned vertical rows.

The downcomer and upcomer headers 17 and 18 of the upper bank 15 are connected to the downcomer and upcomer headers 19 and 20 of the lower bank 16 by means of a row of straight nipples 21 connected into the facing top and bottom walls of the headers and a row of bent nipples 22 connected into the inner side faces of the headers into which the tubes 15 and 16 of the banks are also connected. The combined cross sectional area of these nipples is such with respect to the cross sectional area of the headers that the free area therethrough fairly closely approximates that through the headers so that restriction to flow is minimized, i. e., the combined cross sectional area of the connecting nipples is such with respect to the cross sectional area of the headers that the free area therethrough is greater than, and in fact may be substantially equal to double that of the largest single nipple which it is possible to employ.

Water is led from the upper steam and water drum 23 of the boiler to the downcomer headers 17 by means of a row of downcomer nipples 24 connected at their upper ends into the water space of the drum, and at their lower ends into the upper walls of the headers, and by means of a second row of bent tubes or nipples 25, connected at their upper ends into the water space of the drum, and at their lower ends into the inner side faces of the headers whereby ample water supply is provided to these downcomer headers.

The upcomer headers 18 of the boiler are connected into the steam space of the drum 23 by

20

25

30

35

40

45

50

55

means of a plurality of delivery tubes 26, there being a sufficient number of tubes employed to prevent restriction to flow at this point.

The boiler includes a row of bent tubes 27 connected at one end into the downcomer headers 19 of the lower bank, and at their other ends into the upcomer headers 18 of the upper bank. These tubes extend in parallel relation to the tubes 16 of the lower bank for a portion of their length, then upwardly toward the upper bank, and then in parallel relation to the tubes 15 of the upper bank for the remainder of their length.

The boiler is divided into a plurality of gas passes by a baffle 28 located at the upper portion of the bank 16, a baffle 29 associated with the upright portions of the tubes 27 and extending upwardly through the upper bank, and a baffle 30 associated with the bent tubes or nipples 25 and extending downwardly through the upper bank, so that the gas flow is upwardly through the pass 31, downwardly through the pass 32, and upwardly through the pass 33, from which the gases exit through an off-take 34. The nipples 25 are bent well into the space above the upper bank of boiler tubes so as to provide this last pass. A superheater 35 is located in the pass 31 between the upper and lower banks of tubes, it being noted that the superheater tubes may be inserted and removed through the spaces between adjacent pairs of nipples 21 and 22.

In Fig. 12, I have shown continuous headers with the connecting portions 21a flattened down so as to provide spaces 21b between headers for superheater tube removal. This arrangement may be employed at both ends of the boiler. I also contemplate making either the upcomer or downcomer headers of the boiler continuous from the bottom bank to the top bank without these flattened intermediate portions so as to further eliminate restriction to flow, it being pointed out, however, that this arrangement would only be employed in the headers at one end of the boiler, and that the headers at the other end would be provided with the double nipple arrangement to permit of insertion and removal of superheater tubes at that end.

The furnace or combustion chamber B is defined by steam evaporating tubes, the front wall being defined by a row of upright tubes 36, the rear wall by a row of tubes 37, and each of the side walls by a row of tubes 38, only a few of which are shown at each end of the side wall of Fig. 1. In this instance, the wall tubes are closely spaced with alternate tubes connected at their upper ends into alternate headers of a pair of superposed headers, the upper pairs of headers of the front, rear and side walls being indicated by the reference numerals 39, 40, and 41 respectively. The lower ends of the front, rear and side wall tubes are connected into lower headers 42, 43, and 44 respectively. Due to the close spacing of the tubes, their lower end portions may be swaged down in order to obtain proper ligament strength in the headers.

At the top of the combustion chamber, I provide two rows of tubes 45, in advance of the lower bank of boiler tubes 16. These tubes are arranged generally parallel with the lower bank and incline upwardly from the upper headers 40 of the rear wall 37 to the upcomer headers 18 of the lower bank of the boiler. At the bottom of the combustion chamber, I provide a row of slightly inclined tubes 46 connecting the low-

er header 43 of the rear wall with the lower header 42 of the front wall. In instances where the furnace is of a type to be operated with a bed of molten slag maintained in the bottom thereof, these cooling tubes are preferably closely spaced to retain the bed of slag, or they may be more widely spaced and provided with laterally extending fins to close the space therebetween. Similarly, the upright wall tubes may be provided with such fins. In other types of installations, the bottom cooling tubes 46 may be more widely spaced so as to permit gravitational particles to fall through to an ash pit below.

Water is supplied to the various tubular walls of the furnace from a lower distributing header 47 located adjacent the lower header 43 of the rear wall, and to which water is led from the downcomer headers 19 of the lower bank of the boiler by means of a plurality of downcomer tubes 48, there preferably being one such downcomer tube for each downcomer header 19. These downcomer tubes are provided with expansion bends 49 at their upper portions, and are arranged so that their remaining major portions extend in close parallel relationship to the upright wall tubes 37, these latter portions being located within the rear wall casing. The distributing header 47 is connected to the lower header 43 by means of a plurality of nipples 50, and to the lower headers 44 of the side walls by 30 means of a plurality of bent supply tubes 51. It will thus be seen that the distributing header 47 supplies the tubes 37 of the rear wall through the medium of the nipples 50 and lower header 43, the tubes 38 of the side walls through the medium of the bent tubes 51 and lower headers 44, and the front wall tubes 36 through the medium of the bottom tubes 46 and the lower header 42 of the front wall, and that this distributing header is independent of the furnace wall headers. 40 The advantages of this arrangement reside in that two small and light headers may be employed, that control of distribution to the several walls is provided and that a simple corner construction may be employed. Proportioning of 45 water to the several walls may be controlled by suitably proportioning the total areas of the respective connectors, this being of value since two distinct circulatory paths exist, as will later appear, which must be balanced in resistance 50 losses.

The front wall tubes 36 are connected to deliver into the upcomer headers 18 of the lower bank of the boiler by means of a plurality of bent tubes 52 connected at their lower ends into the pair of upper headers 39 of the front wall and at their upper ends into the lower portion of the upcomer headers 18 of the boiler, the tubes being bent for expansion purposes.

The side wall tubes 38 are connected to deliver 60 into the steam space of the steam and water drum 23 by means of a plurality of riser tubes 53 leading upwardly from the upcomer headers 18 of the side walls to top headers 54 which in turn are connected into the steam space of the drum 23 by 65 means of a plurality of bent tubes 55.

Referring now to the manner of supporting the boiler and the various tubes associated with the furnace, it is to be observed that the boiler A is suspended from fixed supporting members 56 of 70 the structural work E located at the upper portion of the boiler as by means of hangers 57 and 58, and that the front and rear tubular walls of the furnace are suspended from supporting members 59 of the structural work E located adjacent 75

the level of the lower portion of the boiler A through the medium of brackets 68 associated with the upper headers 38 and 40 of the tubular walls. The tubular side walls are similarly suspended from fixed supporting members 61 by brackets 62.

It is to be noted that all of the tubular furnace walls are thus suspended from approximately the same level so that the amount of movement 10 at the lower portion of the walls, due to expansion and contraction thereof, is substantially the same, this being important because of the fact that the bottom tubes 46 connect the lower headers 42 and 43 of the front and rear walls and 15 that they receive additional support from the lower portion of the side walls by means of a plurality of cross beams 63 which in turn receive their support from the lower headers 44 of the side walls. Since the downward expansion of all 20 of the walls is approximately the same, co-operation is ensured between the bottom cross beams and the bottom cooling tubes. The downcomer tubes 48 may also be suspended from the same supporting member as the tubes of the adjacent 25 wall as by means of hangers 64.

It will be seen from the foregoing that the boiler is free to expand downwardly toward the water walls and that the water walls are free to expand downwardly away from the boiler and independently of the expansion of the boiler. The 30 expansion bends in the downcomer tubes 48, the U bent upcomer tubes 52, the bent tubes 45 extending across the top of the furnace, and the flexibility of the riser connections 53 and 55 between the side wall tubes and the steam and water drum 23, enable the above freedom of expansion as between the boiler and water walls without imparting undue strains to the various parts.

Referring to the circulation in the installation, 40 water flows from the steam and water drum 23 through the two rows of nipples 24 and 25 into the downcomer headers 17 of the upper bank 15, then downward through the two rows of nipples 21 and 22 into the downcomer headers 19 of the 45 lower bank 16 and then downwardly through the downcomer tubes 49 into the distributing header 47. From the distributing header, the flow is in two distinct circulatory paths, one being through the front and rear walls and the riser tubes 52 and 45 into the upcomer boiler headers 20, and the other being through the tubes of the 50 side walls directly to the drum 23 by means of the risers 53 and 55. Since the headers of the boiler are interconnected by double nipples, and 55 since ample circulator area is provided between the upper headers 18 and the drum by means of the plurality of delivery tubes 26, I avoid a pressure drop such as would force the level of the water within the headers below the point of entry of the top boiler tubes. It is pointed out that the upper tubes of the upper bank 15, serve 60 as recirculators, i. e., water separated from the steam flows from the upcomer headers 18 to the downcomer headers 17 through these tubes.

65 In Fig. 2, I have illustrated an arrangement in which the side wall tubes 38 are supplied from the lower headers 19 of the boiler by means of downcomer tubes 48 as before, but the front and rear wall tubes 36 and 37 are supplied from 70 the upcomer headers 20 of the boiler by means of downcomer tubes 65 connected at their upper ends into the lower portion of the headers 20 and at their lower ends into the distributing header 66 connected to the lower header 42 of 75 the front wall by means of nipples 67. In this

instance, the flow through the bottom tubes 46 is from the header 42 to the lower header 43 of the rear wall 37. The flow is upwardly through the tubes 36 and 37 and the risers 52 and 45 into the headers 20, it being pointed out that 5 the tubes 52 and 45 are connected into the headers 20 at points above where the downcomer tubes 65 are connected thereto. In this form, I have shown single rows of risers 45 and 52, and have illustrated the wall tubes as equipped 10 with laterally extending fins.

In the modification illustrated in Fig. 3, I have shown all of the wall tubes supplied from downcomer tubes 65 leading from the lower portion 15 of the upcomer headers 20, as illustrated in Fig. 2.

In the modification illustrated in Fig. 4, the side wall tubes 38 are supplied by means of downcomers 65, and the front and rear wall tubes 36 and 37 are supplied by means of the downcomers 48, the connections of which to the boiler are as indicated in Fig. 2.

In some instances, it may be desirable to release some of the steam and water mixture discharged into the upcomer boiler headers by the 25 walls, in order to reduce the resistance to flow of the circuit including the front and rear furnace wall tubes, and such relief may be provided in various ways, as will now appear.

In the arrangement illustrated in Fig. 5, the 30 relief of the upcomer boiler headers 18 in Fig. 1 is accomplished by leading upcomer tubes 68 from the upper portion of the headers 20 to the steam and water drum of the boiler. As illustrated, I prefer to employ a header 69 to which 35 each upcomer header 20 is connected by a nipple 70 and from which the desired number of upcomer tubes 68 lead to the drum. The relief of the headers 18 as by means of the connections 40 illustrated in Fig. 5 has the advantage of not only relieving the circuit including the front and rear water walls, but also of relieving the circuit including the upper bank of boiler tubes 15. Such relief has a tendency to induce more 45 of the bottom tubes of the bank 15 to provide a flow upwardly. Thus the neutral tubes, namely those in which water flow may be either upward or downward, and therefore in danger at times of burning out because of stagnant flow, are put into a cooler gas zone. 50

The resistance to flow may be reduced by the direct relief of the downcomer headers 19 as 55 illustrated in Figs. 6, 8 and 9, by means of a plurality of downcomer tubes 71 leading from the water space of the drum 23 of the boiler 55 to a header 72, which in turn is connected to the downcomer headers by means of nipples 73. In Fig. 8, I have omitted the nipples 74 shown in Fig. 6. As illustrated in Fig. 9, each header 19 may be connected to the header 72 by a nipple 73, and a less number of downcomer tubes 71 may be employed as required for a particular installation. By such relief, circulation in the upper bank of boiler tubes may also be improved 60 in the manner above mentioned. Although the downcomer tubes 71 pass in front of the downcomer headers of the boiler, they are spaced a sufficient distance away so that access to the handholes in the boiler headers may be conveniently had. This also applies to the upcomers 65 of Fig. 5.

In Fig. 10, a modified arrangement of the front wall tubes 36 is illustrated, and the downcomer tubes 65 are suspended from the upper 70 75

portion of certain of the tubes 36 by means of straps 76.

In the modification illustrated in Fig. 7, I have shown a furnace B' of the Dutch Oven type, in which the fuel is introduced through the arch portion 17 by means of suitable burners C'. In this instance, the front wall tubes 36a, the rear wall tubes 37a, and the side wall tubes 38a, are supplied from a single distributing header 41a in the manner described in connection with Fig. 1. The lower headers of the front and rear walls are connected by tubes 46a. Water is led to the distributing header 41a from the header 18, connected to the downcomer headers 19 of the boiler, by means of a plurality of U bent tubes 19 connected at their upper ends into the header 18 and at their lower ends into a cross header 38 and the downcomer tubes 81 leading from the header 38 downwardly to the distributor header 41a. The header 38 is supported on a fixed supporting member 82, and the distributing header 41a is suspended on the downcomer tubes 81. The U bent tubes provide for expansion of the boiler downwardly in the manner above described, and their construction permits of a favorable location for stationary soot blowers 83 for removing slag from the lower rows of boiler tubes and also from the row of riser tubes 46a connecting the rear wall 37a to the uptake headers 28 of the boiler. The side wall tubes 38a may be connected into the steam and water drum of the boiler as illustrated in Fig. 1. The front wall tubes 36a are connected to deliver into the steam and water drum, as by means of riser tubes 84 and 85 which are connected together by a header 86 and to the front wall tubes by a header 81.

In the modification illustrated in Fig. 11, the arrangement of the tubular furnace walls and the supply thereto is very similar to that described in connection with Fig. 3, it being noted, however, that in this instance, the upcomer headers of the lower bank 16a of the boiler are replaced by a drum 88, from the lower portion of which the downcomer tubes 85a lead to the lower distributor header 86. The front wall tubes 38 deliver into the drum 88 and may be provided with nipple extensions 36b so that they will deliver into the drum somewhat above the bottom thereof. The rear wall tubes 37 receive their supply through the medium of the bottom tubes 46, and deliver into the drum 88 through the medium of the riser tubes 45. Flow is upwardly from the drum 88 to the upcomer headers of the upper bank 15, through the nipples 21, and also to the steam and water drum 23 by means of a plurality of upcomer tubes 89. Thus the drum is relieved by these upcomers independently of the upper boiler headers. By employing such a drum, a very effective separating space for the steam and water is provided.

While I have described the advantages to be realized when employing certain features of my invention in connection with the arrangements illustrated in only some of the figures of the drawings, it is to be understood that such advantages may also be had by employing said features in the arrangements of other figures.

I claim:

1. A steam generating installation comprising in combination a boiler having horizontally inclined boiler tubes and upright end headers into which the tubes are connected, a combustion chamber therebelow, upright steam evaporating tubes defining walls of the combustion chamber,

said tubes extending downwardly from the lower portion of the boiler, means for suspending said boiler with freedom to expand downwardly, means for suspending said tubular walls with freedom to expand downwardly, flexible downcomer tubes leading from headers of the boiler for supplying said tubular walls and flexible upcomer tubes leading from said tubular walls to headers of the boiler for delivery.

2. A steam generating installation comprising in combination a boiler having horizontally inclined boiler tubes and upright downcomer and upcomer headers into which the tubes are connected, a combustion chamber therebelow, upright steam evaporating tubes defining walls of the combustion chamber and extending downwardly from the lower portion of the boiler, fixed supports at the level of the upper portion of the boiler, means for suspending the boiler from said supports with freedom to expand downwardly therefrom, fixed supports at the level of the upper portion of the steam evaporating tubes, means for suspending said tubes from said second mentioned supports with freedom to expand downwardly therefrom away from the boiler and independently of the expansion of the boiler, downcomer tubes connected into the downcomer headers of the boiler and to the steam evaporating tubes for supply, and upcomer tubes connected to the steam evaporating tubes and into the upcomer headers of the boiler for delivery, said downcomer and upcomer tubes having expansion bends therein.

3. A steam generating installation comprising in combination a boiler having horizontally inclined boiler tubes and upright sectional end headers into which the tubes are connected, a combustion chamber therebelow, upright steam evaporating tubes defining a plurality of walls of the chamber, headers into which the lower ends of said wall tubes are connected, a distributing header separate from said wall headers, a downcomer tube leading from each section of the sectional headers at one end of the boiler to said distributing header, and a plurality of tubes connecting the distributing header to each of the lower headers of the wall tubes.

4. A steam generating installation comprising in combination a boiler having a steam and water drum, upper and lower banks of horizontally inclined boiler tubes, and upcomer and downcomer end chambers into which the tubes of said banks are connected, a combustion chamber below said boiler, upright steam evaporating tubes defining the front, rear, and side walls of said chamber, means for suspending said boiler and said wall tubes with freedom for independent expansion and contraction, a distributing header at the lower portion of the rear wall, bent downcomer tubes leading from the downcomer end chambers of the lower bank of the boiler to said distributing header, supply tubes leading from said distributing header to the wall tubes, bent upcomer tubes leading from the front and rear wall tubes to the upcomer end chambers of the lower bank of the boiler for delivery, upcomer means leading from the side wall tubes to the steam and water drum of the boiler for delivery and including bent tubes, a multiplicity of nipples connecting the downcomer chambers of the boiler banks together, and a multiplicity of nipples connecting the upcomer chambers of the boiler bank together, said combined nipples having a free area therethrough approximating that through the chambers and greater than that of the largest possible single

nipple which may be employed between headers.

5. A steam generating installation comprising in combination a boiler having a steam and water drum, upcomer and downcomer end headers, and 5 horizontally inclined boiler tubes connecting the headers, a combustion chamber, upright steam evaporating tubes defining the front, rear and side walls of said chamber, lower headers into which the lower ends of said tubes connect, tubes 10 connecting the lower headers of the front and rear walls, upcomer tubes connecting the side wall tubes to the steam and water drum, said front and rear wall tubes having upcomer connection with the upcomer headers of the boiler, 15 and means supplying said tubular walls with water comprising a distributing header separate from the wall headers, downcomer means from the boiler to said distributing header, a plurality of nipples leading from the distributing header 20 to the lower header of each side wall, and a plurality of nipples leading from the distributing header to the lower header of one of the remaining walls.

6. A steam generating installation comprising 25 in combination a boiler having a steam and water drum, upcomer and downcomer end headers, and horizontally inclined boiler tubes connecting the headers, a combustion chamber, steam evaporating tubes defining a plurality of walls of the 30 chamber, headers into which the lower ends of said tubes connect, upcomer tubes connecting certain of the wall tubes to the steam drum, upcomer tubes connecting the remaining wall tubes 35 to the upcomer headers of the boiler, means supplying said tubular walls with water comprising a distributing header separate from the wall headers, downcomer means from the boiler to said distributing header, said downcomer means 40 having expansion bends therein, a plurality of nipples leading from the distributing header to the lower headers of the steam evaporating tubes, means for suspending said boiler, and

means suspending said tubular walls independently of the boiler.

7. A steam generating installation comprising in combination a boiler having a steam and water drum, horizontally inclined boiler tubes, and end 5 headers into which said tubes are connected; a combustion chamber therebelow; upright steam evaporating tubes defining walls of the chamber; upcomer tubes connecting certain of said steam evaporating tubes to the steam and water drum; 10 the remaining of said steam evaporating tubes having upcomer connection to end headers of the boiler; a distributing header; means providing downcomer connection from the boiler to said distributing header; a plurality of tubes providing supply connection from the distributing header to the steam evaporating tubes which have upcomer connection with the steam and water drum; and a plurality of tubes providing supply connection from the distributing header to the 15 remaining steam evaporating tubes.

8. A steam generating installation comprising in combination a boiler having a steam and water drum, horizontally inclined boiler tubes, and upcomer and downcomer end headers into which 25 said tubes are connected; a combustion chamber therebelow; upright steam evaporating tubes defining walls of the chamber; upcomer tubes connecting certain of said steam evaporating tubes to the steam and water drum; the remaining of 30 said steam evaporating tubes having upcomer connection to the upcomer end headers of the boiler; a distributing header; means providing downcomer connection from the downcomer headers of the boiler to said distributing header; 35 a plurality of tubes providing supply connection from the distributing header to the steam evaporating tubes which have upcomer connection with the steam and water drum; and a plurality of tubes providing supply connection from the 40 distributing header to the remaining steam evaporating tubes.

FAY HARRY ROSENCRANTS.
